CHALK SHARPENING MACHINE

David S. Gold, Brooklyn, N. Y.

Application December 16, 1937, Serial No. 180,104

4 Claims. (Cl. 120—94)

This invention relates to new and useful improvements in a chalk sharpening machine.

The invention has for an object to construct a machine as mentioned which is capable of sharpening tailors' chalk. It is proposed to so arrange the machine that a piece of chalk may be engaged therein, and then a handle or other controlling mechanism operated to cause the machine to sharpen the edge of the chalk.

10 Still further the invention proposes to provide the machine with a box-like body having a slot in the top wall through which the piece of chalk may be held, and to provide a sharpening mechanism within the box.

15 Still further it is proposed to provide a drawer or a slide for the box-like body for collecting the shavings of chalk.

Another object of the invention resides in the specific construction of the cutting mechanism 20 for sharpening the chalk.

Still further the invention proposes to so construct the mechanism mentioned in the previous paragraph that it is possible to adjust the same to sharpen the chalk with different kinds of sharp 25 edges.

For further comprehension of the invention, and of the objects and advantages thereof, reference will be had to the following description and accompanying drawing, and to the appended 30 claims in which the various novel features of the invention are more particularly set forth.

In the accompanying drawing forming a material part of this disclosure:—

Fig. 1 is a perspective view of a device constructed according to this invention.

Fig. 2 is a sectional view taken on the line 2—2 of Fig. 1.

Fig. 3 is a horizontal sectional view taken on the line 3—3 of Fig. 2.

40 Fig. 4 is a perspective view of certain portions of the device, particularly the knife and means which supports the knife.

Fig. 5 is a bottom view of Fig. 4.

Fig. 6 is a fragmentary sectional view taken 45 on the line 6—6 of Fig. 4.

Fig. 7 is a fragmentary sectional view taken on the line 7—7 of Fig. 5.

Fig. 8 is a perspective view of a piece of tailors' chalk showing one type of edge sharpened there- 50 on.

Fig. 9 is a fragmentary end elevational view of a piece of tailors' chalk sharpened with another type of edge.

The chalk sharpening machine comprises a 55 box-like body 10 having a slit 11 in its top wall

10^a through which a piece of tailors' chalk, indicated by the dot and dash lines 12^a in Fig. 2, may be held. A knife holding carriage 13 is slidably mounted within the body 10 and beneath the slot 11 and supports a knife 14 for sharpening the edge of the chalk. A means is provided for moving the carriage 13. The chalk shavings are adapted to fall down and be collected in a drawer 15 which extends from one of the walls of the box 10 so that it may be pulled out and emptied 10 when required.

The top wall 10^a of the body is removably held in position by several screws 16 or other fastening elements. The carriage 13 comprises a slide 13^a to which a foundation strip 13^b is secured. 15 This slide and foundation strip are arranged parallel to the slot 13. They are slidably held in this parallel position by several tracks 18 fixedly mounted upon the bottom face of the top wall 10^a.

The carriage 13 also includes a knife support strip 13^c which is also disposed parallel to the foundation strip 13^b and is held in the parallel position by a pair of arms 13^d (see Fig. 5). Each of these arms are pivotally held upon the foundation strip 13^b and the knife support strip 13^c by pintle screws 19. The arrangement is such that the knife support strip 13^c may be moved to various parallel positions with respect to the foundation strip, for example, to the position indicated 20 by the dot and dash lines 13^a in Fig. 5.

The knife 14 is mounted upon the knife support strip 13^c. This knife comprises an L-shaped metallic piece having a vertical arm 14^a formed with a V-shaped slot 14^b. The knife also has a 25 horizontal arm 14^c which is set into a recess 20 formed in the top face of the strip 13^c. The V-shaped opening 14^b extends downwards and communicates with a V-shaped groove 21 formed in the top face of the knife support strip 13^c. 40 The arrangement is such that when a piece of chalk is engaged into the V-shaped cutting portion of the knife it will be correspondingly cut and the freshly cut edge may engage into the V-shaped cut 21 during the cutting operation. 45

A means is provided for holding the knife support strip 13^c in its various parallel positions. This means comprises an arm 22 pivotally supported by a pintle 19 on the knife support strip 13^c and extending under the foundation strip 13^b. 50 This arm 22 is formed with a slot 23. A clamp screw 24 is mounted upon the foundation strip 13^b and engages through a slot 23 and is provided with a clamp nut 25 which may be screwed down tight to hold the strip 22 in various posi- 55

tions. Thus, the knife support strip is similarly held.

The means for moving the carriage comprises a rack bar 26 mounted on the slide 13^a. A pinion 27 meshes with the rack bar 26 and is fixed on a shaft 28 which is rotative through a bearing 29' mounted on the body 10. The shaft 28 extends to the exterior of the box. At its outer end it has a handle 29 by which the pinion 27 may be turned to correspondingly move the knife holding carriage.

In Fig. 8 a piece of tailors' chalk 12 is illustrated having sharpened edges 12^a which are symmetrical on both sides. In Fig. 9 another piece of tailors' chalk 12^{aa} is shown which has its sharpened edge 12^{aa} beveled on one side only. It is possible to form an edge on the back as desired with the sharpening machine.

The operation of the machine is as follows:—
20 Normally, the center of the V-shaped opening 14^b of the knife 14 is aligned with the center of the slot 11. In this condition of the device when a piece of chalk 12' is engaged through the slot 11 and the handle 29 is turned first in one direction and then in the other, the knife 14 will reciprocate and sharpen the bottom edge of the chalk 12' so that the bevel on both sides is symmetrical. The shavings will fall into the drawer 12.

30 When it is desired that the machine sharpen the chalk with a bevel as shown in Fig. 9, then the cover 10^a is loosened and removed, the wing nut 25 is loosened and the knife support strip 13^c is shifted to a new position so that when the parts 35 are assembled it will be in the position indicated in the dot and dash lines 13' in Fig. 2. The clamp nut 25 is then turned down to hold the knife supporting strip in its new position. The parts are re-assembled. Now when the chalk is engaged 40 through the slot it will be beveled on one side only since the center of the V-shaped cutout 14^b is now aligned with one face of the chalk.

The device is also used as a weight, placed on the goods which is to be marked, and the drawer 45 or slide 15 makes it unnecessary to continually walk to a waste receptacle with the chalk shavings.

While I have illustrated and described the preferred embodiments of my invention, it is to be understood that I do not limit myself to the precise constructions herein disclosed, and the right is reserved to all changes and modifications coming within the scope of the invention as defined in the appended claims.

55 Having thus described my invention, what I claim as new, and desire to secure by United States Letters Patent is:—

1. A chalk sharpening machine comprising a box-like body having a slot in its top wall through which a piece of chalk may be held, a knife holding carriage slidably mounted within said body beneath said seat, a knife for sharpening the edge of said chalk mounted on said carriage, and means for moving said carriage, said knife holding carriage comprising a knife support strip upon which said knife is mounted, a foundation strip, several arms connecting said knife support strip to said foundation strip, a slide fixed on said foundation strip, and tracks mounted upon said body and supporting said slide. 5

2. A chalk sharpening machine comprising a box-like body having a slot in its top wall through which a piece of chalk may be held, a knife holding carriage slidably mounted within said body beneath said seat, a knife for sharpening the edge of said chalk mounted on said carriage, means for moving said carriage, a drawer mounted in 20 said body for receiving the shavings from said body, and means for holding said knife support strip in various parallel positions, whereby the knife is similarly held in various specific parallel positions relative to said slot. 25

3. A chalk sharpening machine comprising a box-like body having a slot in its top wall through which a piece of chalk may be held, a knife holding carriage slidably mounted within said body beneath said seat, a knife for sharpening the edge of said chalk mounted on said carriage, means for moving said carriage, a drawer mounted in 30 said body for receiving the shavings from said body, and means for holding said knife support strip in various parallel positions, whereby the knife is similarly held in various specific parallel positions relative to said slot, said carriage being arranged to move parallel to said slot. 35

4. A chalk sharpening machine comprising a box-like body having a slot in its top wall through which a piece of chalk may be held, a knife holding carriage slidably mounted within said body beneath said seat, a knife for sharpening the edge of said chalk mounted on said carriage, means for moving said carriage, a drawer mounted in 40 said body for receiving the shavings from said body, and means for holding said knife support strip in various parallel positions, whereby the knife is similarly held in various specific parallel 45 positions relative to said slot, said carriage being arranged to move parallel to said slot, said arms and said strips forming a parallelogram arranged so that the knife support strip maintains a parallel position in all of its adjusted positions. 50 55
